CLAIM

I claim the ornamental design for a retractable safety barrier, as shown and described.

DESCRIPTION

FIG. 1 is a front perspective view of a retractable safety barrier having my design;

FIG. 2 is a front view of the retractable safety barrier shown in FIG. 1;

FIG. 3 is a rear view of the retractable safety barrier shown in FIG. 1;

FIG. 4 is a left side view of the retractable safety barrier shown in FIG. 1;

FIG. 5 is a right side view of the retractable safety barrier shown in FIG. 1;

FIG. 6 is a top view of a retractable safety barrier having my design shown in FIG. 1;

FIG. 7 is a bottom view of the retractable safety barrier shown in FIG. 1;

FIG. 8 is a front perspective view of the retractable safety barrier shown in FIG. 1, disposed in a doorway and fully extended, with a wall spacing element on an upper spool housing removed;

FIG. 9 is a front perspective view of the retractable safety barrier of FIG. 8, disposed in a doorway and partially extended; and,

FIG. 10 is a rear perspective view of the retractable safety barrier of FIG. 8, disposed in a doorway and partially extended.

Portions of the retractable safety barrier that are illustrated in broken lines form no part of the design claimed. Elements illustrated with dash-dot lines in FIGS. 8-10 are example environment for the retractable safety barrier and form no part of the design claimed.
